SWIMMING DEVICE.

APPLICATION FILED JULY 26, 1921.

Patented Nov. 14, 1922.

2 SHEETS—SHEET 2.

UNITED STATES PATENT OFFICE.

FRANK J. CULLOMER, OF CHICAGO, ILLINOIS.

SWIMMING DEVICE.

Application filed July 26, 1921. Serial No. 487,708.

To all whom it may concern:

Be it known that I, FRANK J. CULLOMER, a citizen of the United States, and a resident of Chicago, in the county of Cook and State 5 of Illinois, have invented a certain new and useful Swimming Device, of which the following is a description, reference being had to the accompanying drawings, which form a part of my specification.

10 My invention relates to a device to be employed by swimmers or bathers, in the nature of a swimming suspender, of such construction as to enable the same to be readily applied so as to in no way interfere with the 15 ability of the swimmer or free movement of the user.

One object of my invention is to provide a construction which will snugly fit about the body and shoulders of the user and permit the same to be worn beneath the outer 20 garments if desired, while at the same time maintaining proper position of the device to admit of free action on the part of the user; the device being so formed that the 25 buoyancy providing portions will support the user in proper position.

Another object of my invention is to provide a construction wherein a plurality of buoyancy providing elements or non-communicating air chambers are provided so that in the event of punctures or disarrangements of one of said elements or air-chambers, the other element or air chamber will remain in tact and not be affected and therefore still enable the user to remain afloat; the construction being adjustable to the body of the user and so formed that the user may readily control the respective 35 buoyancy providing elements or air chambers.

The above enumerated objects and the advantages inherent in my invention will all be more readily comprehended from the detailed description of the drawings, where- 40 in:

Figure 1 is a perspective view of my invention illustrated in buoyancy providing condition.

Figure 2 is a detail cross sectional view 50 taken on the line 2—2 of Figure 1 looking in the direction of the arrows.

Figure 3 is an enlarged view of the shoulder portion of my device, with portions broken away and shown in section.

55 Figure 4 illustrates the application of my improved device and its position on the body

of the user and at the same time discloses a slight modification of fastening means.

My invention in its specific exemplification comprises a pair of inflatable or air-holding members 10, 10, consisting of any suitable air-holding material, impervious to water, preferably rubber formed into the elongated tubular portions 11 and 12, the lower ends whereof are closed and properly sealed to provide air-holding chambers therein. The upper ends of the two portions 11 and 12 are connected by means of a shoulder piece or strap 13 preferably formed integral therewith and cut away on the inner 65 edge or neck side of the strap as shown at 14 so as to properly fit about the shoulders of the user and provide a comparatively narrow strip which will in no way interfere with the free movement of the shoulders and 70 arms of the user. The intermediate or shoulder portion 13 may likewise be formed of rubber, in reality constituting continuations of the two portions 11 and 12 as shown, with the two side walls of the shoulder portions or straps 13, however, preferably cemented or secured together as indicated at 75

15 in Figure 1, in order that the main portion of the shoulder-straps cannot be inflated and thereby provide a more or less cumbersome 80 shoulder portion which would be likely to interfere with proper movement of the user's shoulders. In order, however, that communication between the front and rear tubular portions 11 and 12 may be established, I prefer to provide the rubber tubes indicated at 16, which may consist of comparatively thick rubber and of length sufficient to extend from the upper end of the front tubular portion 11 to the upper portion 85 of the rear tubular portion 12, namely to points beyond the immediate upper ends of the portions 11 and 12 and therefore beyond the shoulders of the user. This rubber tube 16, one of which is provided in each 90 shoulder or strap 13, is secured between the walls or rather within the shoulder portions or straps 13 and properly cemented or secured in place adjacent to what may be termed the outer edges of the shoulder portions or straps 13, as shown in Figure 1, with ends preferably extending a distance within the tubular portions 11 and 12. With this construction, kinking of the shoulder straps or portions and closing off of communication between the front and rear tubular portions 11 and 12 will be practically impos- 95

sible, while proper flow of air from front to rear in both main portions of the device is constantly permitted.

As clearly shown in Figure 1, the device 5 comprises the two main inflatable portions 10, 10 adapted to fit over both shoulders and extend lengthwise of the body of the user as shown in Figure 4 while at the same time being absolutely independent of each other 10 in so far as the air-holding chambers are concerned.

The lower ends of the tubular portions 11 and 12 are provided with a belt, as at 17, formed of any suitable material having the 15 necessary strength; the belt in the particular exemplification being shown provided with pockets or loops as at 18 into which the lower ends of the tubular portions extend and wherein they may be secured in place in any 20 suitable manner; it being found in practice that the ends of the tubular portions will remain in the pockets or loops, without any particular fastening means being employed, when the tubular portions are inflated. It 25 is understood, of course, that the belt may be provided with any suitable fastening means or buckle, as at 19, which will enable the belt to be drawn taut so as to fit snugly about the waist of the user.

30 To maintain the upper portion of the tubular members in proper relation and proper position on the body of the user, the front tubular members 11 of both portions 10 are fastened together in proper spaced relation 35 by means of a strap 20 of any suitable fabric having looped ends as at 21 of such size as to enable the complete or maximum inflation of the tubular or air-holding portions 11; while the back tubular portions 12 of both 40 members 10 are likewise secured together and held in proper spaced relation by a strap or band 22 having the looped ends 23 for the passage of the tubular portions 12 and also of such dimensions as to permit maximum 45 inflation of said tubular portions.

The straps 20 and 22 may be adjustable lengthwise of the tubular portions 11 and 12 so as to be moved toward or farther from the upper ends of the tubular portions in 50 accordance with the desires and physic of the user.

The upper end of each front tubular portion 11 and preferably at what may be termed the upper inner edge thereof is provided with a suitable air-valve as at 24 having the lower end of its casing or shell properly and immovably secured within the tubular portion as shown at 25 in Figure 1, while the lower end of the shell or casing is preferably provided with a rubber tube extension as at 26.

By employing the rubber tubes 16 and 26 as shown and described, it is apparent that the device is reenforced at points where the 65 same is apt to be subjected to more or less

pressure and flexing. At the same time the method of securing the air-valves 24 with the more or less heavy tubing 26 ensures the air-valves remaining in upright or vertical position where they will be readily accessible 70 to the mouth of the user so that he can inflate the device after the same has been placed about the body, while the construction described also provides a grasping point for the user, when it is desired to inject air, 75 which will not interfere with the introduction of the air. Furthermore, the method of securing the valves in place will prevent their bending laterally or downwardly out of easy reach necessitating bending the 80 valves upwardly; the valves will constantly be held in vertical position near the mouth of the wearer to permit inflation of the device while the user is in the water and the device is in place on his body. 85

In Figure 4 I show a slight modification or addition to my improved device in that the device is shown provided with suitable crotch-strings or straps 27 which may be passed through suitable eyelets provided in 90 the bottom ends of the main portions 11 and 12, or secured in any other suitable manner at points beneath the air-holding part of the portions 11 and 12; the straps or strings 27 being provided with suitable adjusting 95 means or buckles as at 28 in order that the straps or strings may be drawn taut. The strings or straps may be desired to properly hold the device down in position, especially where the user's waist line is such that the 100 main belt 17 would not prevent the upward creeping movement of the device induced by constant movement of the body of the user. In most instances, the strings or straps may be eliminated, although they may be of such 105 nature as to in no way interfere with the free movement of the body of the user and the strings may, if desired, be employed instead of the main belt 17.

The air-admitting valves 24 may be of a 110 well known construction at present employed and therefore require no specific description nor disclosure, while the tubular portions 11 and 12 may vary in cross-sectional dimensions so as to provide proper supporting capacity when completely inflated. With the construction shown and described it is apparent that separate buoyancy providing chambers or air-holding elements are provided so that in the event of a rupture or 115 puncture in one side of the device the entire supporting capacity of the swimming suspender will not be destroyed, while at the same time the construction is such that its position on the body of the user will be 120 maintained. 125

I have illustrated what I believe to be the simplest and best embodiment of my invention, having described the same in terms which are employed merely as terms of de- 130

scription and not as terms of limitation, as structural modifications are possible and may be made without, however, departing from the spirit of my invention.

5 What I claim is:—

1. A device of the character described, comprising a plurality of inflatable tubular members adapted to extend intermediate of the shoulders and waist at front and rear 45
 10 of the body of the user, said tubular members being arranged in pairs, the two pairs being arranged in spaced and non-communicating relation, the front and rear members of the same pair being provided at 50
 15 their upper ends with integral non-inflatable shoulder portions, an air-conveying tube secured in each shoulder portion, extending from the upper end of the front tubular member to the upper part of the rear tubular 55
 20 member, an upstanding air inlet valve secured to the upper end of each front tubular member, and means whereby the two pairs of tubular members are maintained in spaced relation and the device secured to the 60
 25 body of the user.

2. A device of the character described, comprising a plurality of elongated inflatable tubular members adapted to be disposed lengthwise of the chest and back, intermediate of the shoulders and waist of the user and arranged in pairs, non-inflatable shoulder portions extending intermediate of the outer upper ends of the tubular members whereby the front and rear members are secured together in non-communicating pairs, a flexible tube secured within each shoulder portion along the outer edge thereof and extending from a point below the upper end of the front tubular member to a point beneath the upper end of the correlated back 65
 30
 35
 40

tubular member whereby communication between the front and rear members is established, adjustable means whereby the tubular members, both front and rear, will be held against separating movement and maintained in predetermined spaced relation, an air-inlet valve secured to the upper and inner opposing side of each front tubular member and having a rigid portion enclosed in the tubular member so as to adapt said 50
 55 valve to extend upwardly into proximity with the chin of the user, and means secured about the lower ends of the tubular members whereby the device may be adjustably secured to the body of the user. 55

3. A device of the character described, comprising two pairs of inflatable tubular portions adapted to extend at front and rear of the body of the user intermediate of the shoulders and waist, the two pairs being 60
 spaced apart in non-communicating relation, the inflatable portions of each pair being connected together at their upper ends by flat non-inflatable shoulder portions offset from the upper inner ends of the inflatable tubular portions, an air-conveying tube secured within the shoulder portions for establishing communication between the front and rear inflatable portions of each pair, an upstanding air valve secured in the offset upper end 65
 70 of each front tubular portion, with a portion of the valve casing embedded in said front tubular portion, and means attached to all of the tubular portions whereby they are maintained in place and secured to the body 75
 of the user.
